UNITED STATES PATENT OFFICE

2,487,481

TOY GUN

Samuel A. Savitt, Chicago, Ill.

Application April 13, 1945, Serial No. 588,088.

1 Claim. (Cl. 46—10)

1

The present invention relates generally to toy guns. More particularly the invention relates to that type of toy gun which is designed or adapted to be used by a child and comprises a housing together with a barrel having one end thereof connected to, and communicating with, the housing.

One object of the invention is to provide a toy gun of this type which is generally of new and improved construction, embodies a novel arrangement of parts and is characterized by the fact that it comprises in addition to the housing and barrel a rotary device in the housing for producing a loud noise or report similar to that attendant to the firing of a regular gun, and a rotary device in the outer end of the barrel for producing sparks in simulation of the explosive discharge that occurs in connection with discharge or firing of a regular gun.

Another object of the invention is to provide a toy gun of the last mentioned type and character in which the rotary noise or report producing device in the housing is provided with manually manipulable means for driving it and the rotary spark producing device in the outer end of the barrel is connected for conjoint drive with the noise producing device to the end that drive of the latter will result in concurrent functioning of both devices.

A further object of the invention is to provide a toy gun of the type and character last mentioned in which the means for driving the noise producing device is in the form of a crank, the handle part of which is exteriorly disposed with respect to the housing and the means whereby the spark producing device is connected for conjoint drive with the noise producing device is in the form of a chain and sprocket connection which extends through and is partially housed within the barrel.

A still further object of the invention is to provide a toy gun which is essentially simple in design and construction and may be produced at a comparatively low cost.

Other objects of the invention and the various advantages and characteristics of the present toy gun will be apparent from a consideration of the following detailed description.

The invention consists in the several novel features which are hereinafter set forth and are more particularly defined by the claim at the conclusion hereof.

In the drawing which accompanies and forms a part of this specification or disclosure and in which like numerals of reference denote corresponding parts throughout the several views:

Figure 1 is a side elevation of a toy tank having applied thereto a gun embodying the invention;

Figure 2 is a vertical longitudinal section of 60 hole defining portion of the housing side wall.

2

the gun illustrating in detail the construction, design and manner of mounting of the rotary noise producing device in the housing and the spark producing device in the outer end of the barrel;

Figure 3 is an inverted plan view of the gun, certain parts being broken away and certain other parts being shown in section for purposes of illustration; and

Figure 4 is an enlarged section of the rotary spark producing device.

The gun which is shown in the drawing constitutes the preferred form or embodiment of the invention. It is essentially a toy for amusing a child and is illustrated in connection with, and as forming a part of, a toy tank 5. The tank forms no part of the invention and is illustrated merely to show one article with which the gun may be used. It serves as a portable or mobile support for the gun and comprises a body 6 and a pair of laterally spaced roller supported endless tread elements 7 at the bottom of the body. As its main or principal components the gun comprises a housing 8, a barrel 9, a crank 10, a noise or report producing device 11, and a spark producing device 12.

The housing 8 is in the form of a turret and is suitably mounted on the upper portion of the tank body 6 so that it is capable of rotating about a vertical axis. It serves as an enclosure for the noise or report producing device 11 and consists of a dome shaped top wall 13 and a depending cylindrical side wall 14. The side wall is preferably formed integrally with the rim or marginal portion of the top wall 13 and defines with said top wall a compartment 15.

The barrel 9 is formed of tubular metal stock and is proportioned to simulate a regular gun barrel. It extends horizontally and is tapered from one end thereof to the other. The large end of the barrel extends through and fits snugly within a circular aperture 16 in the cylindrical side wall 14 of the turret shaped housing 8. It is open in order that the interior of the barrel is in communication with the compartment 15. The outer or small end of the barrel is open and, as hereafter described, carries the spark producing device 12.

The crank 10 serves as a medium or instrumentality for driving or operating the device 11 and comprises a shaft 17, a radially extending arm 18 at one end of the shaft 17 and a handle 19 on the outer end of the arm. The shaft 17 of the crank is disposed at right angles to the barrel 9 and has the portion thereof directly inwards of the arm 18 journalled in a bearing 20. The latter extends through a cylindrical hole 21 in the side wall 14 of the housing and is suitably secured against axial displacement with respect to the

The crank arm 18 and the handle 19 are disposed exteriorly of the housing 8 in order that the handle is accessible when it is desired to turn the crank in connection with operation of the gun. The inner end of the crank shaft 17, i. e., the end that is disposed within the compartment 15 in the gun housing, extends substantially all the way across the compartment and is in horizontal alignment with the barrel 9. It preferably is arranged in intersecting relation with the vertical axis of the housing and is suitably held against axial displacement with respect to the bearing 20. The crank 10 is arranged so that the crank arm 18 and handle 19 are positioned at the right hand side of the barrel. As hereinafter described the crank is adapted in connection with operation of the gun, to be turned in a clockwise direction as viewed in Figures 1 and 2 of the drawing.

The noise or report producing device 11 is disposed within the compartment 15 and comprises a collar 22 and a leaf spring 23. The collar is fixedly mounted on the inner end of the crank shaft 17, and is adapted to turn or revolve in response to rotation of the crank. It is located at the left hand side of the barrel 9, and embodies a pair of integral outwardly extending lugs 24. The latter are positioned one diametrically opposite the other and are provided with pointed or wedge shaped outer ends. The front or leading surfaces of the lugs are curved or arcuate and the rear or trailing surfaces are flat and extend substantially radially with respect to the collar 22. The leaf spring 23 is in longitudinal alignment with the lugs 24 and normally extends rearwards and upwards, as shown in Figure 2. The front end of the spring is disposed in a V-shaped notch 25 in the lower end of the cylindrical side wall 14 of the turret shaped housing 8 and is fixedly secured in place by means of a screw 26 which extends through a hole in the front end of the spring and projects into the slot defining portion of the housing side wall. The rear end of the spring is adapted successively to contact the lugs 24 in response to turning of the collar 22. When the collar is turned in response to rotation of the crank the lugs 24 successively engage and flex downwards the rear end of the leaf spring 23. Each time one of the lugs is turned into contact with the spring the spring is flexed downwards as the result of the camming effect of the curved or arcuate leading surface of the lug. The spring is flexed downward until its rear end reaches the tip of the lug. In response to further rotation of the lug the tip of the lug passes the rear end of the spring with the result that the spring snaps upward past the flat trailing surface of the lug and strikes against the collar with sufficient force to produce a comparatively loud noise or report. Each time the crank 10 is rotated two reports are made by the spring. Because the lugs 24 on the collar have flat substantially radially extending surfaces they function as ratchet teeth and so coat with the rear end of the leaf spring 23 as to prevent reverse or counterclockwise turning of the crank 10.

The spark producing device 12 is located at the outer or small end of the barrel 9 and comprises a wheel 27 and a piece 28 of flint. The wheel 27 is formed of steel and has outwardly extending teeth 29 on its periphery. It is located in the outer end of the barrel and is fixedly secured to the central portion of a horizontally extending shaft 30, the ends of which extend through, and are journalled in, coaxial holes in the outer end of the gun barrel. The flint piece 28 is located be-

neath and is in contact with the bottom portion of the wheel 27 and is slidably mounted in a vertically extending tube 31. The upper end of the tube extends through a hole 32 in the bottom portion of the outer end of the gun barrel and is soldered or welded in place. The flint piece is urged upwards into contact with the steel wheel 27 by way of a helical compression spring 33 in the tube 31. The upper end of the spring is provided with a follower 34 which abuts against the lower end of the flint piece 28. The lower end of the spring abuts against an adjusting screw 35 which extends into the lower end of the tube 31. Said lower end of the tube has an internal or female screw thread which is in engagement with the male screw thread on the screw and coacts therewith to shift the screw axially in response to rotation or turning of the screw. By turning the screw in one direction or the other the tension of the compression spring 33 may be adjusted. When the steel wheel 27 is rotated in a counterclockwise direction as viewed in Figures 2 and 3, its teeth 29 scrape against the flint piece 28 and result in sparks being discharged from the outer end of the barrel. The steel wheel 27 is driven conjointly with the lug equipped collar 22 of the noise or report producing device 11 by means of a sprocket and chain connection 36 and a pair of meshing gears 37 and 38. The sprocket and chain connection 36 comprises a sprocket wheel 39, a sprocket wheel 40 and an endless chain 41. The sprocket wheel 39 is mounted on, and fixedly secured to, the crank shaft 17. It is aligned with the barrel 9 and is disposed between the lug equipped collar 22 and the bearing 20 for the crank shaft. The sprocket wheel 40 is located in the outer end of the barrel 9 directly inwards of the steel wheel 27 of the spark producing device 12 and is fixedly secured to a horizontally extending shaft 42, the ends of which extend through, and are journalled in, coaxial holes in the outer end of the barrel 9. The endless chain 41 is trained around the two sprocket wheels 39 and 40 and has the major portion of its upper and lower reaches extending through the barrel 9, as shown in Figures 2 and 3. The gear 37 is located at one side of the sprocket wheel 40 and is pinned, keyed, or otherwise fixedly secured to the shaft 42. The gear 38 is located at one side of the steel wheel 27 and is suitably fixedly secured to the shaft 30. The two gears 37 and 38 cause the steel wheel 27 to be rotated or turned in a counterclockwise direction when the crank shaft 17 is turned clockwise as viewed in Figures 1 and 2.

When the crank 10 is turned it results in conjoint actuation of the noise or report producing device 11 and the spark producing device 12. As heretofore pointed out, each complete revolution of the crank results in the leaf spring 23 on the device 11 making two loud reports. Because of the manner in which the lugs 24 coat with the spring 23 turning of the crank is pronouncedly intermittent even though a constant force is applied to the handle 19. Because of the intermittent turning of the crank the spark producing device 12 operates intermittently and produces sparks in timed relation with the reports that are produced by the device 11.

The herein described toy gun is essentially simple in design and construction and may be produced at a comparatively low cost. Due to the fact that the gun includes the devices 11 and 12 it serves when operated to produce reports and

flashes like those that are produced during firing of a regular gun.

Whereas the gun has been described in connection with, and as forming a part of, a toy tank it is to be understood that it may be used with any other toy vehicle or it may be made to simulate a rifle, cannon or machine gun. It is also to be understood that the invention is not to be restricted to the details set forth since these may be modified within the scope of the appended claim without departing from the spirit and scope of the invention.

Having thus described the invention what I claim as new and desire to secure by Letters Patent is:

As a new article of manufacture, a toy gun comprising a housing, an open ended barrel having one end thereof connected to, and communicating with the interior of, the housing, a hand crank having the shaft thereof extending into the housing and its crank arm disposed exteriorly of the housing, a report producing device positioned in the housing and consisting of a leaf spring having one end thereof anchored to the housing and in addition a collar mounted 25 fixedly on the crank shaft and embodying radially extending lugs adapted in response to drive of the collar by the crank shaft to be brought successively into contact with the other end of

the spring and shaped and arranged so as to contact with said other end of the spring in such manner as to permit the crank to rotate freely in one direction only, a spark producing device carried by the other end of the barrel and embodying a rotary wheel in said other end of the barrel, and a driving connection for connecting the two devices for conjoint operation consisting of a sprocket wheel mounted fixedly on said shaft of the crank, a sprocket wheel disposed in said other end of the barrel and connected to drive the wheel of the sparking device, and an endless chain extending around the two sprocket wheels and disposed for the most part in the barrel.
